R. R. ATCHLEY

FENDER ATTACHMENT FOR CULTIVATORS

Filed Oct. 16. 1923

UNITED STATES PATENT OFFICE.

ROY R. ATCHLEY, OF DE KALE, TEXAS.

FENDER ATTACHMENT FOR CULTIVATORS.

Application filed October 16, 1923. Serial No. 668,820.

To all whom it may concern:

Be it known that ROY R. ATCHLEY, a citizen of the United States of America, residing at De Kalb, in the county of Bowie and 5 State of Texas, has invented new and useful Improvements in Fender Attachments for Cultivators, of which the following is a specification.

The purpose of the invention is to provide 10 a device for use in connection with cultivators and other toothed ground working devices whereby the fender used in connection with such devices may be readily adjusted to properly position it for the character 15 of work which it has to perform.

With this general object in view the invention consists in a construction and combination of parts of which a preferred embodiment is shown in the accompanying 20 drawings without defining the limits of the invention.

In the drawings:

Figure 1 is a view in side elevation showing the application of the invention, it being 25 attached to one of the teeth of a cultivator of the spring tooth variety.

Figure 2 is a front elevational view of the structure of Figure 1, the tooth being shown in section.

30 Figure 3 is a top plan view of the structure of Figure 1.

Figure 4 is a section on the line 4—4 of Figure 1.

35 Figure 5 is a section on the line 5—5 of Figure 4.

The device is designed as a means for attaching the fender 1 to the cultivator or scratcher tooth 2 and embodies a triangular body piece 3 reduced in thickness, as indicated at 4, to provide a shoulder 5 to abut the edge of the shank of the tooth. The clamp plate 6 is employed and secured to the body piece by bolts 7, the clamp plate lying against the shank of the tooth on the 45 side opposite the reduced portion 4 when the bolts are screwed on to effect a firm clamping engagement on the shank of the tooth.

A circular head 8 is formed as an integral 50 part of the body piece 1 and is disposed in a plane at right angles to the plane of the latter, the outer face of the head being formed with a plurality of apertures 9 arranged in a circle concentric with the head 55 through the center of which there is formed an eye or opening for the reception of a

bolt 10 by means of which the standard 11 is secured to the head, the latter being provided with studs 12 for engagement in the apertures 9. Obviously, the position of the 60 arm may be varied by loosening the bolt 10 sufficiently to permit the withdrawal of the studs 12 from the apertures 9, when the standard may be swung forwardly or rearwardly to the desired angular position. The 65 reengagement of the studs then with two new diametrically opposite holes maintains the desired adjustment after the tightening of the bolt which positively secures the standard in place. 70

The fender 1 is carried by a fender arm 15 and the latter at its upper end is swingingly supported on a bolt 16 passing through a central eye in a disk head 17 carried at the upper end of the standard, the disk head 75 being provided with uniformly spaced lateral apertures or openings 18 for selective engagement with diametrically disposed laterally projecting studs 19 carried by a plate 20 which is secured to the disk head 80 17 by the bolt 16. The plate on the side facing the head is recessed, as indicated at 21, the recess being formed on divergent lines to provide for lateral swing of the arm 15 and yet limiting the pivotal movement of the latter. 85

In the initial adjustment of the device, the studs 19 are engaged with such holes or apertures 18 as will limit the downward movement of the arm to position the fender 90 at the point desired. Obviously, then, the fender may be elevated upon encountering any obstruction in the operation of the machine, the diverging side walls of the recess 21 permitting swinging movement of the 95 fender arm 15 upward to permit the fender to clear the obstruction.

Having described the invention, what is claimed is:

1. The combination with the ground 100 working element of a ground working tool and the fender therefor of which the latter is provided with an arm, of a member secured to the shank of the ground working element, a standard carried by said member and connected with the fender arm, a single bolt securing said standard to said member, and positive means securing said standard in various positions of adjustment upon the tightening of said bolt. 105

2. The combination with a ground working element of a ground working tool and 110

the fender therefor of which the latter is provided with an arm, of a member clamped to the shank of said ground working element and formed with an integral head disposed in a plane at right angles to the body portion of said member, said head being formed on one face with a plurality of apertures arranged in a circle concentric with the head, a standard connected with the

fender arm, and a bolt passing through said standard and through a central hole formed in said head, said standard being provided with studs selectively engageable with any two diametrically opposite apertures in said head upon the tightening of said bolt. 10
15

In testimony whereof he affixes his signature.

ROY R. ATCHLEY.
